UNITED STATES PATENT OFFICE.

STERLING H. CAMPBELL, OF ST. LOUIS, MISSOURI, ASSIGNOR TO RAILWAY DEVICES COMPANY, OF ST. LOUIS, MISSOURI, A CORPORATION OF MISSOURI.

ANGLE-COCK HOLDER.

1,148,751.

Specification of Letters Patent. Patented Aug. 3, 1915.

Application filed March 17, 1913. Serial No. 754,765.

To all whom it may concern:

Be it known that I, STERLING Houser CAMPBELL, a citizen of the United States of America, residing at the city of St. Louis, State of Missouri, have invented a certain new and useful Angle-Cock Holder; of which the following is such a full, clear, and exact description as will enable any one skilled in the art to which it appertains to make and use the same, reference being had to the accompanying drawings, forming part of this specification.

My invention relates to an angle cock holder and has for its object the production of an angle cock holder which, while simple in construction, will not only hold the angle cock against both rotation and forward movement but, at the same time, will clamp the train pipe so as to prevent movement between the train pipe and angle cock.

In the accompanying drawings, which illustrate some forms of angle cock holders made in accordance with my invention, Figure 1 is a side elevation showing the preferred form; Fig. 2 is a section on the line 2-2 of Fig. 1; Fig. 3 is a section on the line 3-3 of Fig. 1, the angle cock and train pipe being omitted; Figs. 4 and 5 are front and side views respectively showing a slight modification; and Figs. 6 and 7 are views similar to Figs. 4 and 5, but showing a still further modification.

Like marks of reference refer to similar parts in the several views of the drawings. 10 represents the end sill of the car, 11 the train pipe, and 12 the angle cock. The angle cock 12 is provided with the usual hexagonal head 13. Secured to the end sill 10 by means of bolts 14 and nuts 15 is an L-shaped plate 16. The horizontal portion of this plate 16 is adapted to bear upon the top face of the head 13 of the angle cock. In the forms shown in Figs. 1 to 3 inclusive, this plate 16 is provided with a downwardly extending flange 17 which is adapted to engage with the front face of the angle cock head and thus prevent the angle cock from forward motion.

In the form of my device shown in Figs. 1 to 3, a loop 18 surrounds the train pipe 11 and has threaded ends 19 projecting through openings in the horizontal portion of the plate 16. These threaded ends 19 are engaged by nuts 20. Carried by the loop 18 is the angular housing 21 which embraces

three sides of the angle cock head 13, as best shown in Fig. 2. The housing 21 is provided with a flange 22 adapted to engage with the front face of the angle cock head 13 in order to prevent the forward movement of the angle cock. This flange 22 is provided with a recess 23 adjacent to the point where the angle cock head joins the body. The object of this recess 23 is to allow the proper seating of the angle cock head in the housing in case there is an excess of metal at this part of the angle cock as is often the case.

In the modification shown in Figs. 4 and 5, the angular housing 21 is omitted, the loop 18 being, in this case, formed of a simple rod of metal, the flange 17 on the plate 16 being depended upon to prevent the forward movement of the angle cock.

The modification shown in Figs. 6 and 7 is like that shown in Figs. 1 to 3 except that the flange 17 is omitted from the plate 16.

The operation of my device will be evident. In order to secure the angle cock and train pipe in position, it is only necessary to pass the ends 19 of the loop 18 through the openings in the plate 16 and tighten the nuts 20.

The holder, while simple in construction, not only prevents the forward movement and rotation of the angle cock, but, at the same time, firmly clamps the train pipe in position.

Having fully described my invention, what I claim as new and desire to secure by Letters-Patent of the United States is:

1. In an angle cock holder, a retaining member adapted to be carried by the car, said retaining member being provided with a flat bearing surface, and a loop carried by said retaining member and adapted to surround the train pipe for holding a flat surface of the angle cock head against the flat bearing surface of the retaining member.

2. In an angle cock holder, a retaining member adapted to be carried by the car, said retaining member being provided with a flat bearing surface, a loop carried by said retaining member and adapted to surround the train pipe for holding a flat surface of the angle cock head against the flat bearing surface of the retaining member, and means for preventing forward movement of the angle cock.

3. In an angle cock holder, the combination

tion with an angle plate adapted to be secured to the end of a car and forming a retaining member, of an angle cock having one face of its head bearing against said retaining member, and a loop surrounding the train pipe adjacent to the angle cock and having its ends projecting through said retaining member, said loop and retaining member coöperating to form a clamping device and one of said parts being provided with a flange to prevent forward movement of the angle cock.

4. In an angle cock holder, the combination with an angle plate adapted to be secured to the end of a car and forming a retaining member, of an angle cock having one face of its head bearing against said retaining member, and a loop surrounding the train pipe adjacent to the angle cock and having its ends projecting through said retaining member, said loop and retaining member coöperating to form a clamping device, said retaining member being provided with a flange to prevent forward movement of the angle cock.

5. In an angle cock holder, the combina-

tion with an angle plate adapted to be secured to the end of a car and forming a retaining member, of an angle cock having one face of its head bearing against said retaining member, and a loop surrounding the train pipe adjacent to the angle cock and having its ends projecting through said retaining member, said loop and retaining member coöperating to form a clamping device, both of said parts being provided with flanges to prevent the forward movement of the angle cock.

6. The combination with a train pipe, of an angle cock on said train pipe, an angular member carried by the car, and a vertically disposed U-bolt carried by said angular member adapted to engage the train pipe for holding a flat surface of said angle cock in close contact with said angular member.

In testimony whereof, I have hereunto set my hand and affixed my seal in the presence of the two subscribing witnesses.

STERLING H. CAMPBELL. [L. S.]
